US00D953253S

(12) **United States Design Patent** (10) **Patent No.:** **US D953,253 S**
Cestonaro et al. (45) **Date of Patent:** **** May 31, 2022**

(54) **BATTERY PACK**

(71) Applicant: **Positec Power Tools (Suzhou) Co., Ltd.**, Suzhou (CN)

(72) Inventors: **Andrea Cestonaro**, Vicenza (IT); **Yanan Liu**, Suzhou (CN)

(73) Assignee: **Positec Power Tools (Suzhou) Co., Ltd.**, Suzhou (CN)

(**) Term: **15 Years**

(21) Appl. No.: **29/738,081**

(22) Filed: **Jun. 15, 2020**

(30) **Foreign Application Priority Data**

Dec. 16, 2019 (CN) 201930701898.9

(57) **CLAIM**

The ornamental design for a battery pack, as shown and described.

DESCRIPTION

FIG. 1 is a front perspective view of a first embodiment of a battery pack showing our new design;

FIG. 2 is a rear elevational view of the first embodiment thereof;

FIG. 3 is a front elevational view of the first embodiment thereof;

FIG. 4 is a left side view of the first embodiment thereof;

FIG. 5 is a right side view of the first embodiment thereof;

FIG. 6 is a top plan view of the first embodiment thereof;

FIG. 7 is a bottom plan view of the first embodiment thereof;

FIG. 8 is a front perspective view of a second embodiment of a battery pack showing our new design;

FIG. 9 is a front elevational view of the second embodiment thereof;

FIG. 10 is a rear elevational view of the second embodiment thereof;

FIG. 11 is a right side view of the second embodiment thereof;

FIG. 12 is a left side view of the second embodiment thereof;

FIG. 13 is a top plan view of the second embodiment thereof; and,

FIG. 14 is a bottom plan view of the second embodiment thereof.

The broken lines shown in the drawings illustrate portions of the battery pack which form no part of the claimed design.

1 Claim, 14 Drawing Sheets
